DESIGN FOR A GAME BOARD OR SIMILAR ARTICLE

Vincent A. R. Primavera, New York, N. Y.

Application October 30, 1943, Serial No. 111,546

Term of patent 14 years

To all whom it may concern:

Be it known that I, Vincent A. R. Primavera, a citizen of the United States, residing at New York city, in the county of New York and State of New York, have invented a new, original, and ornamental Design for a Game Board or Similar Article, of which the following is a specification, reference being had to the accompanying drawing, forming part thereof.

In the drawing, the single figure is a top plan view of a game board, showing my new design.

The game board is of conventional thickness.

I claim:

The ornamental design for a game board or similar article, substantially as shown and described.

VINCENT A. R. PRIMAVERA.
